UNITED STATES PATENT OFFICE.

LOUIS S. BACH, OF CHICAGO, ILLINOIS.

NECKTIE.

1,294,025.

Specification of Letters Patent. Patented Feb. 11, 1919.

Application filed February 7, 1918. Serial No. 215,661.

To all whom it may concern:

Be it known that I, LOUIS S. BACH, a resident of Chicago, in the county of Cook and State of Illinois, have invented certain new and useful Improvements in Neckties, of which the following is a specification.

This invention relates to new and useful improvements in neckties and has for its object the provision of an article of this character which may be tied in the usual and ordinary manner by the wearer and after having been tied may be removed from and placed upon the neck without untying, and yet be capable of all of the adjustments that are present in the ties that have heretofore been used, and which must be completely untied for removal.

In this manner the life of the necktie is prolonged by the elimination of the constant tying and untying now necessary, and at the same time the objectionable features and characteristics of the ready-tied scarf are not present.

Furthermore when the knot becomes soiled or otherwise damaged the present scarf may be retied at another point in its length to present a fresh, clean and undamaged knot.

With the above and other objects in view, as will be apparent, this invention consists in the combination and arrangement of parts and features, all as hereinafter more fully described, claimed, and illustrated in the accompanying drawings, wherein:

Figure 1 is a perspective view of a collar, partly broken away, illustrating one form of the tie or scarf forming the subject matter of the present invention in conjunction therewith;

Fig. 2 is a similar view illustrating another form of the present invention in conjunction with a collar;

Fig. 3 is an elevation of the connection used in the form of the invention shown in Fig. 2; and

Figs. 4 and 5 are details of the snap catches used in both of the shown forms of the invention, but illustrated as adapted in that form shown in Figs. 2 and 3.

The present invention is exemplified in the drawing as being carried out in a four-in-hand tie, and while it may be as readily applied to a bow tie, the present purposes will be amply served by the application

illustrated and the following description will be so limited.

In carrying out the present device, a four-in-hand tie of any usual and characteristic design including the outer scarf end or section 10, the inner scarf end or section 11, connected together by the relatively narrow neck band 12, and toward which the scarf ends taper, constitutes the basis upon which the improved structure forming the subject matter hereof is predicated.

In that form of the invention shown in Fig. 1, the neck band 12 of the tie is severed as at 13 near the outer scarf end or section 11, and the adjoining ends so created are provided with the elements of a snap catch 14, such as that illustrated in detail in Figs. 4 and 5.

Thus the ends created by the cut 13 may be overlapped and the elements of the catch 14 interlocked, thereby forming a solid neck band. When the parts are so arranged the tie may be placed about the collar C and tied in the usual manner, whereby a knot 15 is produced in the outer scarf end or section 12 that is slidable for adjustment to the neck on the inner scarf end or section 11. After the tie has so been tied and adjusted, it presents the appearance of, and in fact is, an individually tied and adjusted scarf. In order to remove the tie the knot 15 is slipped downwardly upon the inner scarf end or section 11, to loosen the neck band, and the elements of the snap catch 14 released, thereby permitting the tie to be removed without further disturbing the knot 15. It may be then replaced by inserting the neck band 10, with its ends disconnected, in the collar, fastening the collar, connecting the elements of the snap catch 14, and adjusting the knob 15 in the orthodox manner.

In its use and functions the form or adaptation of the invention shown in Figs. 2 to 5 inclusive is identical with that shown in Fig. 1. Here the neck band 12 is severed near the outer scarf end or section 11, to create the ends 12^a and 12^b, which in the use and operation of the tie are separated one from the other. The end 12^a of the neck band 12 has a tab 16 (Figs. 3 and 4) thereon which carries the male element 14^a of a snap catch. On the opposite end 12^b of the neck band 12 is provided a similar tab 18 that is looped through the eye 19 of

2
a pivot plate 20. The pin 21 of this pivot plate 20 acts as a permanent pivot for a carrier 22, formed of small wire or other suitable material, bent to create a major loop 23 and minor loop 24, the latter being especially adapted to permanently and yet pivotally engage the pin 21 of the plate 20.

5 A tape 25 is attached to the major loop 23 of the carrier 22 and by means of the 10 female element 14^b of a snap catch, carried by the free end thereof, coöoperating with the male element 14^a constitutes a detachable connection between the ends 12^a and 12^b of the neck band 12.

15 This form of tie when used for the first time is placed about the collar with the elements 14^a and 14^b of the snap catch connected and the tie is tied and adjusted in the usual manner. To remove the tie from 20 the neck and collar the elements 14^a and 14^b of the snap catch are disconnected after the knot 15 has been slid downwardly on the inner scarf end or section 11. It at once becomes manifest that after the scarf has 25 once been tied it can be replaced by locating the neck band with the tape 25 disconnected from the tab 16 about the collar, after which the collar may be attached, at which time the tape 25 will extend downwardly as illustrated in dotted lines in Fig. 30 2.

2. The end 12^a and the tab 16 may then be pulled down slightly and attached to the tape 25 by means of the elements 14^a and 14^b of the snap catch, while these operating 35 portions of the tie are more or less free of the collar. The knot 15 may then be adjusted, which adjustment draws the tape 25 into alinement with the remainder of the neck band 12 where it forms a continuation 40 thereof and is located entirely within the

collar or in its proper place with respect to the collar. Thus the neck band 12 is retained in its normal position in the collar C, and is not materially displaced for the purpose of connecting the ends 12^a and 12^b of 45 the neck band 12. At the same time the ends 12^a and 12^b of the neck band may be secured together in a manner which is not hampered because of the fact that these ends are located entirely within the collar. Hence, 50 a connection between the elements 14^a and 14^b of the snap catch is freely established without interference from the collar.

What is claimed is:—

1. As an article of manufacture, a necktie 55 constituting a neck band terminating in scarf ends, said neck band being severed and having a tape pivoted to one of the ends created by severing the neck band, said tape having means for detachably securing it at 60 its free end to the remaining end so created.

2. As an article of manufacture, a necktie constituting a neck band terminating in scarf ends, said neck band being severed, a 65 tape pivoted to one of the ends so created and having an element of a snap catch secured to the free end thereof for engagement with the corresponding element of the snap catch secured to the remaining end of the neck band created by severing the latter. 70

3. As an article of manufacture a necktie constituting a neck band terminating in scarf ends, said neck band being severed, a tab secured to one of the ends so created and having an element of the snap catch secured thereto, a tape pivoted to the opposite end created by severing the necktie and provided at its free terminal with the corresponding element of a snap catch. 75

LOUIS S. BACH.
